E. BAUER

COIL BODY FOR ELECTRICAL APPARATUS

Filed Oct. 6, 1924

Inventor:
Edwin Bauer
By - B. Singer, Atty.

UNITED STATES PATENT OFFICE.

EDWIN BAUER, OF ZUG, SWITZERLAND, ASSIGNOR TO LANDIS & GYR A.-G., OF ZUG, SWITZERLAND (A SWISS FIRM).

COIL BODY FOR ELECTRICAL APPARATUS.

Application filed October 6, 1924, Serial No. 742,054, and in Switzerland October 9, 1923.

With the known types of spools, particularly with those which are employed in electrical apparatus, it is difficult to securely attach the inner end of the winding to the 5 spool and it has been necessary to resort to unsatisfactory makeshifts in order to fasten this end of the winding and at the same time to avoid damaging the end of the coil which is left free for connecting up.

10 The object of the present invention is to eliminate the aforementioned disadvantages.

The invention relates to a spool for electrical apparatus, in whose core is a groove by means of which the end of the winding 15 can be securely fixed and smooth winding can be obtained.

The drawing shows one arrangement for carrying out the invention.

Fig. 1 shows the spool in elevation,

20 Fig. 2 gives a section of the spool along the line A—A in Fig. 1,

Fig. 3 shows a section along the line B—B in Fig. 1.

The spool, which may be made of moulding material, has a core 1 and two flanges 2, 2'. The core, the outer surface of which is circular, has a central rectangular opening. Owing to this arrangement, the thickness of the wall of the core is a maximum 30 at four sections, and at one of these sections a groove 5 is provided, running parallel to the longitudinal axis of the spool. This groove extends as far as the flange 2' and a hole is provided in the latter on a level 35 with the bottom of the groove. Near to the flange 2', the edge formed by the intersection of the cylindrical surface of the core and one wall of the groove is rounded off as shown at 7. In the groove, at the end nearest to the flange 2, is a projection, which does not, however, rise flush with the outer surface 4 of the core.

The wire with which the coil is wound can be brought into the groove 5, and led around 45 the projection 8, the inner end of the coil thus being securely attached to the spool. With this arrangement the wire used for the coil would project at one end through the hole 6, and at the other end would be 50 led over the rounded surface 7 on to the sur-

face of the core. For this purpose a stiffer wire than that used for the coil itself can be employed, as shown in dotted lines in Fig. 1. This wire is laid in the groove 5 in the manner described and the actual wire 55 used for the coil is attached to it. After the end of the coil has been firmly attached to the spool, the groove is preferably covered by a strip 9 of insulating material fitted into it, and the winding can then be begun. 60

The spool need not necessarily be of circular cross section. It might, for example, be oval or approximately angular.

The spool to which the present invention relates can be employed in all kinds of electrical apparatus and can be made of any suitable material. As has already been mentioned, it might be made of moulding material, but it could equally well be made of any other suitable substance. It could, for 70 instance, be turned from wood, in which case the groove would be milled out.

What I wish to secure by Letters Patent is:

1. A spool for an electro-magnet or the like, comprising a core and flanges on the end thereof, said core being provided in its face with a longitudinal groove extending to one of the flanges, for the reception of a doubled wire, a projection in said 75 groove near its inner end to lie between the leads of the doubled wire and an opening through the flange at the outer end of said groove for the passage of one lead of the wire. 80

2. A spool for an electro-magnet or the like, comprising a core and flanges on the end thereof, said core being provided in its face with a longitudinal groove extending to one of the flanges, for the reception of a 85 doubled wire, a projection in said groove near its inner end to lie between the leads of the doubled wire and an opening through the flange at the outer end of said groove for the passage of one lead of the wire, the 90 said core being provided with a rounded surface at one side of said groove and near the last named flange.

In witness whereof I affix my signature.
EDWIN BAUER.
